WIPING CONTACT ROTARY SWITCH

Howard F. Mason, Los Angeles, Calif., assignor to Mason Electric Corporation, Los Angeles, Calif., a corporation of California

Filed Mar. 19, 1962, Ser. No. 180,639
14 Claims. (Cl. 200—11)

The present invention relates in general to switches and, more particularly, to rotary switches, general objects of the invention being to provide a completely reliable rotary switch which will maintain uniform contact resistances throughout long periods of use, which is positively detented in its operating positions, which may be composed of more than one section each separately detented instead of utilizing a master detent for all sections, which is completely versatile in that it can be made up in various configurations for different usages with the same parts, and the like.

An important object of the invention is to provide a rotary switch which includes, or each section of which includes: an annular stator providing an annular, concave contact path; the contact path including an annular contact row of circumferentially spaced, stationary contacts; the contact path including an annular insulating row or circumferentially spaced, insulating segments which is parallel to the contact row; the insulating segments being axially aligned, respectively, with the circumferential spaces between the stationary contacts; a rotor within the stator and rotatable about the axis thereof; a movable contact carried by and movable radially relative to the rotor and engaging the contact path; spring means biasing the movable contact radially outwardly into engagement with the contact path; the stator providing an annular detent path paralleling the contact and insulating rows of the contact path; the detent path having circumferentially spaced points of maximum radius axially aligned, respectively, with the stationary contacts; the detent path having circumferentially spaced points of minimum radius axially aligned, respectively, with the insulating segments; a detent carried by and movable radially relative to the rotor and engaging the detent path; and spring means biasing the detent radially outwardly into engagement with the detent path.

It will be noted that, with the foregoing construction, detenting is accomplished in a positive manner within the switch itself, or within each section of the switch itself. Another important advantage of the foregoing construction is that the movable contact cannot track metal from the stationary contact onto the insulating segments because of the fact that the row of insulating segments is axially offset from and parallel to the row of stationary contacts. Thus, different portions of the movable contact engage the stationary contacts and the insulating segments to avoid metal tracking.

Another object of the invention is to provide a rotary switch of the foregoing nature wherein there are two rows of stationary contacts and two corresponding rows of insulating segments all axially spaced apart, the axial dimension of the movable contact being sufficient to bridge the contact and insulating rows. A related object is to provide a stator wherein the insulating rows are between the contact rows and wherein the detent path is between the insulating rows.

Still another object of the invention is to provide a rotary switch wherein the movable contact is a wiping contact slidably engaging the contact path.

A further object of the invention is to provide a stator

2

which is divided into two halves in a transverse plane coinciding with the midplane of the detent path, which simplifies manufacture.

Yet another object is to provide a rotary switch wherein the radius of the insulating segments is slightly less than the radius of the stationary contacts so that the insulating segments displace the wiping contact radially inwardly out of engagement with the stationary contacts as the rotor rotates. Thus, in effect, the insulating segments lift the wiping contact from the stationary contacts, thereby producing a faster break.

An additional object of the invention is to provide a construction wherein the spring means for biasing the wiping contact radially outwardly into engagement with the contact path includes two compression springs substantially radially aligned with the respective rows of stationary contacts. With this construction, the wiping contact is pressed against each pair of stationary contacts by corresponding springs. A related object is to provide springs having substantially constant spring rates so that wear does not significantly affect contact pressure.

Another object of the invention is to provide a construction wherein the wiping contact is radially slidable in a longitudinally oriented, radially extending groove in the rotor.

A further object of the invention is to provide a construction wherein each wiping contact includes two circumferentially abutting, wiping contact elements carried in the corresponding groove in the rotor, the wiping contact elements having convex wiping shoes slidably engaging the contact path and respectively extending circumferentially in opposite directions. With this construction, a make before break or transfer type of switching is achieved. Alternatively, where each wiping contact includes but a single contact element, a break before make type of switching is achieved.

Another object in connection with the double-contact-element structure discussed above is to provide independent springs for the two contact elements, whereby each contact element is biased into engagement with the contact path independently. A further object in this connection is to provide two compression springs in engagement with one contact element of each pair in radial alignment with the stationary contact rows, and to provide a single compression spring in engagement with the midpoint of the other contact element of such pair.

Yet another object is to provide a rotary switch wherein the diameter of the rotor approaches the inside diameter of the stator to provide a small, arc quenching annular clearance therebetween.

The foregoing objects, advantages, features and results of the present invention, together with various other objects, advantages, features and results thereof which will be quite evident to those skilled in the switch art in the light of this disclosure, may be achieved with the exemplary embodiments of the invention described in detail hereinafter and illustrated in the accompanying drawings, wherein:

FIG. 1 is a side elevational view on a reduced scale illustrating a wiping contact rotary switch which embodies the invention;

FIG. 2 is a longitudinal sectional view of the rotary switch of FIG. 1 on an enlarged scale;

FIG. 3 is a fragmentary perspective view of an annular stator of the rotary switch of the invention;

FIG. 4 is a perspective view of a rotor of the rotary switch of the invention;

FIG. 5 is a fragmentary sectional view taken approxi-

mately along the irregular arrowed line 5—5 of FIG. 2;

FIG. 6 is a view similar to FIG. 5, but showing various parts in different operating positions;

FIGS. 7 and 8 are views respectively similar to FIGS. 5 and 6, but showing another embodiment of the invention;

FIG. 9 is a fragmentary sectional view taken approximately along the arrowed line 9—9 of FIG. 7; and

FIG. 10 is a perspective view of a double-contact-element wiping contact incorporated in the embodiment of FIGS. 7 to 9 of the drawings.

The rotary switch of the invention is designated generally by the numeral 20 and includes a generally cylindrical housing 22 having an actuating shaft 24 projecting axially therefrom. The housing 22 includes an annular stator 26 within which a rotor 28 is rotatable, the rotor being mounted on and keyed to the shaft 24, as by being telescoped onto a squared portion of the shaft.

The housing 22 includes two axially spaced end walls 30 and 32 respectively providing bearings 34 and 36 for the shaft 24 and receiving the annular stator 26 therebetween, the stator being separated from the end walls 30 and 32 by annular insulating spacers 38 and 40, respectively. The various components of the housing 22 are clamped together by screws 42 extending therethrough. The bearing 36 has the form of a bushing which is externally threaded to permit panel mounting of the switch 20 in a conventional manner, and the projecting end of the shaft 24 is designed to accept a knob, not shown, for manual actuation. However, other mounting and actuating arrangements may be used.

The internal surface of the annular stator 26 provides an annular, concave contact path 44 for one or more wiping contacts carried by the rotor 28, only one wiping contact being shown for convenience and being designated by the numeral 46. The contact path includes two axially spaced, parallel, annular contact rows of circumferentially spaced, stationary contacts 48 respectively embedded in annular stator halves 50 having adjacent ends in abutting relation in the midplane of the stator. The stationary contacts 48 of each contact row may be molded directly into the corresponding stator half 50 and project radially outwardly through such stator half to permit external wiring connections thereto. The stationary contacts 48 of each contact row may be separate, or interconnected in various ways, depending upon the use to be made of the switch 20.

The axial dimension of the wiping contact 46 is sufficient for it to bridge the two rows of stationary contacts 48, each stationary contact being axially aligned with a corresponding stationary contact in the other row. With this bridging type of action, the stationary contacts 48 of one row may all be interconnected, as shown in FIG. 3, and the stationary contacts of the other row may all be separate to control separate circuits. However, various of the stationary contacts of the other row may also be interconnected in some instances.

Axially intermediate the rows of stationary contacts 48 are two axially spaced, parallel, annular rows of circumferentially spaced, insulating segments 52. The insulating segments of each insulating row are axially aligned, respectively, with the circumferential spaces between the stationary contacts 48 of each contact row. Thus, the wiping contact 46, in moving circumferentially from one pair of stationary contacts 48 to the next, slides over the intervening pair of insulating segments 52. Since the rows of insulating segments 52 are axially intermediate and axially spaced from the rows of stationary contacts 48, the portions of the wiping contact 46 which engage the insulating segments 52 are spaced axially from the portions of the wiping contact which engage the stationary contacts 48. This misalignment thus prevents metal tracking from the stationary contacts 48 across the insulating segments 52, which is an important feature.

As best shown in FIGS. 5 and 6 of the drawings, the radius of the insulating segments 52 is slightly less than the radius of the stationary contacts 48 so that the insulating segments displace the wiping contact 46 radially inwardly out of engagement with the stationary contacts 48 as the rotor 28 rotates. Thus, the pair of insulating segments 52 intervening two adjacent pairs of stationary contacts 48 in effect lifts the wiping contact 46 out of engagement with the first pair of stationary contacts so as to rapidly increase the gap between the wiping contact 46 and the pair of stationary contacts which the wiping contact is disengaging. Arcing is therefore minimized, which is an important feature. It might also be pointed out in this connection that the radial clearance between the rotor 28 and the contact path 44 is small so that it has an arc quenching effect as the wiping contact 46 is displaced circumferentially away from each pair of stationary contacts 48.

The annular stator 26 provides an annular detent path 54 located between the rows of insulating segments 52 and bisected by the transverse dividing plane provided by the two halves 50 of the stator. The detent path 54 includes circumferentially spaced points or peaks 56 of minimum radius axially aligned, respectively, with the insulating segments 52 of each row, and circumferentially spaced points or valleys 58 of maximum radius axially aligned, respectively, with the stationary contacts 48 of each contact row. The rotor 28 carries one or more radially movable detents, one being shown and being identified by the numeral 60, slidably circumferentially along the detent path 54 over the peaks 56 and across the valleys 58 thereof. As will be apparent, when the detent 60 is in one of the valleys 58, it releasably locks the rotor 28 in one of its operating positions, wherein the wiping contact 46 bridges the stationary contacts 48 of one pair thereof. This condition is shown in FIG. 5 of the drawings. FIG. 6 of the drawings shows the detent 60 riding over one of the peaks 56 as the wiping contact 46 traverses an adjacent pair of insulating segments 52.

The rotor 28 is provided with a plurality of circumferentially spaced, longitudinally oriented, radially extending grooves 62 which are spaced apart circumferentially a distance equal to the circumferential spacing of the pair of stationary contacts 48 and the pairs of insulating segments 52.

The rotor 28 is provided with three axially spaced, radially extending holes in register with each groove 62 and wider than such groove so that, in effect, each such hole forms opposed, radially extending grooves in the respective side walls of each groove 62. The middle hole which coincides with each groove 62 is designated by the numeral 64, the other two being identified by the numeral 66. The holes 64 communicate at their inner ends with smaller, coaxial, radial holes 68 in the rotor 28.

The purpose of the foregoing construction of the coinciding grooves 62 and holes 64 and 66 is to provide a construction wherein each groove may receive either a wiping contact 46, or a detent 60, without modification. Also, as will become apparent in connection with a subsequent description of the embodiment of FIGS. 7 to 10 of the drawings, each groove 62 is capable of accepting a double-contact-element wiping contact 70 without modification. Thus, the same grooves 62 are capable of receiving various elements, which is an important feature of the invention.

The wiping contact 46 is generally U-shaped in side elevation, as best shown in FIG. 2 of the drawings, and includes two arms respectively radially slidable in the portions of one of the grooves 62 which are axially outwardly of the outer holes 66. The wiping contact 46 is biased radially outwardly into positive engagement with the contact path 44 by two compression coil springs 72 respectively disposed in and secured to the rotor 28 by the corresponding axially outer holes 66. The springs 72 are seated at their inner ends on the radially inner wall

of the corresponding groove 62, and are seated at their outer ends against the crossbar of the U-shaped wiping contact 46. With this construction, a very simple means of assembling the wiping contact 46 and the springs 72 with the rotor 28 is provided, which is an important feature of the invention.

It will be noted that the axially outer holes 66 are substantially in radial alignment with the rows of stationary contacts 48. Consequently, the springs 72 respectively bias the wiping contact 46 directly into engagement with the stationary contacts 48 of each pair. As hereinbefore indicated, the spring rates of the springs 72 are substantially constant so that the spring force with which the wiping contact is radially biased remains substantially constant even after appreciable wear.

The detent 60 has the form of a pin which is radially slideable in the middle hole 64 of the particular groove 62 in which it is disposed. The detent 60 is provided at its inner end with a reduced-diameter stem 74 which extends radially inwardly into the corresponding hole 68 in the rotor 28. A compression coil spring 76 is disposed within the corresponding middle hole 64 and encircles the stem 74 of the detent 60, being seated at its inner end against the inner end of the corresponding hole 64, and being seated at its outer end against an annular shoulder formed at the outer end of the stem 74. Again, this provides a very simple means of assembling the detent 60 and its spring 76 with the rotor 28.

Also, as hereinbefore pointed out, the same groove 62, with the foregoing construction, can accept either a wiping contact 46, or a detent 60, without modification. Thus, the same parts can be used in various arrangements, which is an important feature.

As will be apparent from FIGS. 5 and 6 of the drawings, the wiping contact 46 operates with a break before 35 make type of action. The present invention is equally adaptable to a make before break or transfer type of action by utilizing a different construction for the wiping contact, wherein the circumferential extent of the wiping contact is larger. The preferred construction for this 40 purpose, which includes the hereinbefore-referred-to double-contact-element wiping contact 70, is shown in FIGS. 7 to 10 of the drawings.

Referring thereto, the wiping contact 70 includes two wiping contact elements 82 and 84 both disposed in one 45 of the grooves 62 in the rotor 28 in circumferentially abutting relation. The contact elements 82 and 84 are respectively provided with convex wiping shoes 86 and 88 which are slidably engageable with the contact path 44 and which extend circumferentially in opposite directions. 50 The wiping shoes 86 and 88 have sufficient circumferential width to bridge two adjacent pairs of the stationary contacts 48 simultaneously, as shown in FIG. 8 of the drawings, to provide the desired make before break or transfer type of action.

The contact elements 82 and 84 are of similar construction, but oppositely oriented, and both are generally U-shaped in side elevation, being similar to the wiping contact 46 in this respect. The contact element 82 is biased radially outwardly by two compression coil springs 60 90 disposed in the outer holes 66 coinciding with the corresponding groove 62. The springs 90 are seated at their inner ends against the inner ends of the holes 66, and are seated at their outer ends against the crossbar of the contact element 82. Thus, the contact element 82 is 65 spring biased in the same manner as the wiping contact 46.

Engagement of the springs 90 with the contact element 84 is prevented by radially-outwardly-relieving the crossbar of the contact element 84, as indicated at 92. Intermediate the reliefs 92, the contact element 84 is provided with a radially-inwardly-extending tab 94 which extends radially inwardly beyond the crossbar of the contact element 82. A compression coil spring 96 disposed in the corresponding central hole 64 is seated against the tab 94 and against the inner end of such central hole. Conse- 70 75

quently, the spring 96 acts only on the contact element 84, applying substantially equal contact pressures on both stationary contacts 48 of the particular pair which engages. To provide the same contact pressure for the contact element 84 as for the contact element 82, the spring 96 may be heavier than the springs 90.

Although exemplary embodiments of the invention have been disclosed herein for purposes of illustration, it will be understood that various changes, modifications, and substitutions may be incorporated in such embodiments without departing from the spirit of the invention as defined by the claims which follow:

I claim:

1. In a switch, the combination of:
  - (a) a stationary member providing a contact path;
  - (b) said contact path including a contact row of spaced, stationary contacts;
  - (c) said contact path including an insulating row of spaced, insulating segments which is parallel to and spaced from said contact row;
  - (d) said insulating segments being laterally aligned, respectively, with the spaces between said stationary contacts;
  - (e) a movable member movable along said contact path;
  - (f) a movable contact carried by said movable member and movable toward and away from and engageable with said contact path;
  - (g) spring means biasing said movable contact into engagement with said contact path;
  - (h) said stationary member providing a detent path paralleling said contact and insulating rows of said contact path;
  - (i) said detent path having spaced valleys laterally aligned, respectively, with said stationary contacts;
  - (j) said detent path having spaced peaks laterally aligned, respectively, with said insulating segments;
  - (k) a detent carried by said movable member and movable toward and away from and engageable with said detent path; and
  - (l) spring means biasing said detent into engagement with said detent path.
2. In a rotary switch, the combination of:
  - (a) an annular stator providing an annular, concave contact path;
  - (b) said contact path including an annular contact row of circumferentially spaced, stationary contacts;
  - (c) said contact path including an annular insulating row of circumferentially spaced, insulating segments which is parallel to and spaced axially from said contact row;
  - (d) said insulating segments being axially aligned, respectively, with the circumferential spaces between said stationary contacts;
  - (e) a rotor within said stator and rotatable about the axis thereof;
  - (f) a movable contact carried by and movable radially relative to said rotor and engaging said contact path;
  - (g) spring means biasing said movable contact radially outwardly into engagement with said contact path;
  - (h) said stator providing an annular detent path paralleling said contact and insulating rows of said contact path;
  - (i) said detent path having circumferentially spaced points of maximum radius axially aligned, respectively, with said stationary contacts;
  - (j) said detent path having circumferentially spaced points of minimum radius axially aligned, respectively, with said insulating segments;
  - (k) a detent carried by and movable radially relative to said rotor and engaging said detent path; and
  - (l) spring means biasing said detent radially outwardly into engagement with said detent path.

3. In a rotary switch, the combination of:

- (a) an annular stator providing an annular, concave contact path;
- (b) said contact path including two axially spaced, parallel, annular contact rows of circumferentially spaced, stationary contacts;
- (c) said stationary contacts of one of said contact rows being axially aligned, respectively, with said stationary contacts of the other of said contact rows;
- (d) said contact path including two axially spaced, parallel, annular insulating rows of circumferentially spaced, insulating segments spaced axially from said contact rows, respectively;
- (e) said insulating segments of one of said insulating rows being axially aligned, respectively, with said insulating segments of the other of said insulating rows;
- (f) said insulating segments of each of said insulating rows being axially aligned, respectively, with the circumferential spaces between said stationary contacts of each of said contact rows;
- (g) a rotor within said stator and rotatable about the axis thereof;
- (h) a movable contact carried by and movable radially relative to said rotor and engaging said contact path;
- (i) the axial dimension of said movable contact being sufficient to bridge said contact rows;
- (j) spring means biasing said movable contact radially outwardly into engagement with said contact path;
- (k) said stator providing an annular detent path paralleling said contact and insulating rows of said contact path;
- (l) said detent path having circumferentially spaced points of maximum radius axially aligned, respectively, with said stationary contacts of each of said contact rows;
- (m) said detent path having circumferentially spaced points of minimum radius axially aligned, respectively, with said insulating segments of each of said insulating rows;
- (n) a detent carried by and movable radially relative to said rotor and engaging said detent path; and
- (o) springs means biasing said detent radially outwardly into engagement with said detent path.

4. In a wiping contact rotary switch, the combination of:

- (a) an annular stator providing an annular, concave contact path;
- (b) said contact path including two axially spaced, parallel, annular contact rows of circumferentially spaced, stationary contacts;
- (c) said stationary contacts of one of said contact rows being axially aligned, respectively, with said stationary contacts of the other of said contact rows;
- (d) said contact path including two axially spaced, parallel, annular insulating rows of circumferentially spaced, insulating segments spaced axially from said contact rows, respectively;
- (e) said insulating segments of one of said insulating rows being axially aligned, respectively, with said insulating segments of the other of said insulating rows;
- (f) said insulating segments of each of said insulating rows being axially aligned, respectively, with the circumferential spaces between said stationary contacts of each of said contact rows;
- (g) a rotor within said stator and rotatable about the axis thereof;
- (h) a wiping contact carried by and movable radially relative to said rotor and slidably engaging said contact path;
- (i) the axial dimension of said wiping contact being sufficient to bridge said contact rows;
- (j) spring means biasing said wiping contact radially outwardly into engagement with said contact path;
- (k) said stator providing an annular detent path paralleling said contact and insulating rows of said contact path.

leling said contact and insulating rows of said contact path;

- (l) said detent path having circumferentially spaced points of maximum radius axially aligned, respectively, with said stationary contacts of each of said contact rows;
- (m) said detent path having circumferentially spaced points of minimum radius axially aligned, respectively, with said insulating segments of each of said insulating rows;
- (n) a detent carrier by and movable radially relative to said rotor and engaging said detent path; and
- (o) spring means biasing said detent radially outwardly into engagement with said detent path.

5. In a wiping contact rotary switch, the combination of:

- (a) an annular stator providing an annular, concave contact path;
- (b) said contact path including two axially spaced, parallel, annular contact rows of circumferentially spaced, stationary contacts;
- (c) said stationary contacts of one of said contact rows being axially aligned, respectively, with said stationary contacts of the other of said contact rows;
- (d) said contact path including two axially spaced, parallel, annular insulating rows of circumferentially spaced, insulating segments spaced axially from said contact rows, respectively;
- (e) said insulaing segments of one of said insulating rows being axially aligned, respectively, with said insulating segments of the other of said insulating rows;
- (f) said insulating segments of each of said insulating rows being axially aligned, respectively, with the circumferential spaces between said stationary contacts of each of said contact rows;
- (g) said insulating rows being between said contact rows;
- (h) a rotor within said stator and rotatable about the axis thereof;
- (i) a wiping contact carried by and movable radially relative to said rotor and slidably engaging said contact path;
- (j) the axial dimension of said wiping contact being sufficient to bridge said contact rows;
- (k) spring means biasing said wiping contact radially outwardly into engagement with said contact path;
- (l) said stator providing an annular detent path between said insulating rows of said contact path;
- (m) said detent path having circumferentially spaced points of maximum radius axially aligned, respectively, with said stationary contacts of each of said contact rows;
- (n) said detent path having circumferentially spaced points of minimum radius axially aligned, respectively, with said insulating segments of each of said insulating rows;
- (o) a detent carried by and movable radially relative to said rotor and engaging said detent path; and
- (p) spring means biasing said detent radially outwardly into engagement with said detent path.

6. In a wiping contact rotary switch, the combination of:

- (a) an annular stator providing an annular, concave contact path;
- (b) said contact path including two axially spaced, parallel, annular contact rows of circumferentially spaced, stationary contacts;
- (c) said stationary contacts of one of said contact rows being axially aligned, respectively with said stationary contacts of the other of said contact rows;
- (d) said contact path including two axially spaced, parallel, annular insulating rows of circumferentially spaced, insulating segments spaced axially from said contact rows, respectively;

- (e) said insulating segments of one of said insulating rows being axially aligned, respectively, with said insulating segments of the other of said insulating rows;
  - (f) said insulating segments of each of said insulating rows being axially aligned, respectively, with the circumferential spaces between said stationary contacts of each of said contact rows;
  - (g) said insulating rows being between said contact rows;
  - (h) a rotor within said stator and rotatable about the axis thereof;
  - (i) a wiping contact carried by and movable radially relative to said rotor and slidably engaging said contact path;
  - (j) the axial dimension of said wiping contact being sufficient to bridge said contact rows;
  - (k) spring means biasing said wiping contact radially outwardly into engagement with said contact path;
  - (l) said stator providing an annular detent path between said insulating rows of said contact path;
  - (m) said stator being divided into two halves in a transverse plane coinciding with the midplane of said detent path;
  - (n) said detent path having circumferentially spaced points of maximum radius axially aligned, respectively, with said stationary contacts of each of said contact rows;
  - (o) said detent path having circumferentially spaced points of minimum radius axially aligned, respectively, with said insulating segments of each of said insulating rows;
  - (p) a detent carried by and movable radially relative to said rotor and engaging said detent path; and
  - (q) spring means biasing said detent radially outwardly into engagement with said detent path.
7. In a wiping contact rotary switch, the combination of:
- (a) an annular stator providing an annular, concave contact path;
  - (b) said contact path including two axially spaced, parallel, annular contact rows of circumferentially spaced, stationary contacts;
  - (c) said stationary contacts of one of said contact rows being axially aligned, respectively, with said stationary contacts of the other of said contact rows;
  - (d) said contact path including two axially spaced, parallel, annular insulating rows of circumferentially spaced, insulating segments spaced axially from said contact rows, respectively;
  - (e) said insulating segments of one of said insulating rows being axially aligned, respectively, with said insulating segments of the other of said insulating rows;
  - (f) said insulating segments of each of said insulating rows being axially aligned, respectively, with the circumferential spaces between said stationary contact of each of said contact rows;
  - (g) said insulating rows being between said contact rows;
  - (h) a rotor within said stator and rotatable about the axis thereof;
  - (i) a wiping contact carried by and movable radially relative to said rotor and slidably engaging said contact path;
  - (j) the axial dimension of said wiping contact being sufficient to bridge said contact rows;
  - (k) spring means biasing said wiping contact radially outwardly into engagement with said contact path;
  - (l) the radius of said insulating segments being slightly less than the radius of said stationary contacts so that said insulating segments displace said wiping contact radially inwardly out of engagement with said stationary contacts as said rotor rotates;

- (m) said stator providing an annular detent path between said insulating rows of said contact path;
  - (n) said detent path having circumferentially spaced points of maximum radius axially aligned, respectively, with said stationary contacts of each of said contact rows;
  - (o) said detent path having circumferentially spaced points of minimum radius axially aligned, respectively, with said insulating segments of each of said insulating rows;
  - (p) a detent carried by and movable radially relative to said rotor and engaging said detent path; and
  - (q) spring means biasing said detent radially outwardly into engagement with said detent path.
8. In a wiping contact rotary switch, the combination of:
- (a) an annular stator providing an annular, concave contact path;
  - (b) said contact path including two axially spaced, parallel, annular contact rows of circumferentially spaced, stationary contacts;
  - (c) said stationary contacts of one of said contact rows being axially aligned, respectively, with said stationary contacts of the other of said contact rows
  - (d) said contact path including two axially spaced, parallel, annular insulating rows of circumferentially spaced, insulating segments spaced axially from said contact rows, respectively;
  - (e) said insulating segments of one of said insulating rows being axially aligned, respectively, with said insulating segments of the other of said insulating rows;
  - (f) said insulating segments of each of said insulating rows being axially aligned, respectively, with the circumferential spaces between said stationary contacts of each of said contact rows;
  - (g) said insulating rows being between said contact rows;
  - (h) a rotor within said stator and rotatable about the axis thereof;
  - (i) a wiping contact carried by and movable radially relative to said rotor and slidably engaging said contact path;
  - (j) the axial dimension of said wiping contact being sufficient to bridge said contact rows;
  - (k) spring means biasing said wiping contact radially outwardly into engagement with said contact path;
  - (l) said spring means including two compression springs respectively substantially radially aligned with said contact rows;
  - (m) said stator providing an annular detent path between said insulating rows of said contact path;
  - (n) said detent path having circumferentially spaced points of maximum radius axially aligned, respectively, with said stationary contacts of each of said contact rows;
  - (o) said detent path having circumferentially spaced points of minimum radius axially aligned, respectively, with said insulating segments of each of said insulating rows;
  - (p) a detent carried by and movable radially relative to said rotor and engaging said detent path; and
  - (q) spring means biasing said detent radially outwardly into engagement with said detent path.
9. In a wiping contact rotary switch, the combination of:
- (a) an annular stator providing an annular, concave contact path;
  - (b) said contact path including two axially spaced, parallel, annular contact rows of circumferentially spaced, stationary contacts;
  - (c) said stationary contacts of one of said contact rows being axially aligned, respectively, with said stationary contacts of the other of said contact rows;
  - (d) said contact path including two axially spaced, parallel, annular insulating rows of circumferentially spaced, insulating segments, part

13

- being axially aligned, respectively, with said stationary contacts of the other of said contact rows;
- (d) said contact path including two axially spaced, parallel, annular insulating rows of circumferentially spaced, insulating segments spaced axially from said contact rows, respectively; 5
- (e) said insulating segments of one of said insulating rows being axially aligned, respectively, with said insulating segments of the other of said insulating rows;
- (f) said insulating segments of each of said insulating rows being axially aligned, respectively, with the circumferential spaces between said stationary contacts of each of said contact rows; 10
- (g) said insulating rows being between said contact rows;
- (h) a rotor within said stator and rotatable about the axis thereof;
- (i) said rotor being provided therein with a longitudinally oriented, radially extending groove; 15
- (j) two circumferentially abutting wiping contact elements carried in said groove and movable radially therein relative to each other and to said rotor and slidably engaging said contact path;
- (k) the axial dimension of said wiping contact elements being sufficient to bridge said contact rows; 20
- (l) said wiping contact elements having convex wiping shoes slidably engaging said contact path and extending circumferentially in opposite directions;
- (m) spring means individually biasing said wiping contact elements radially outwardly into engagement with said contact path; 30
- (n) said spring means including two compression springs engaging one of said wiping contact elements and respectively substantially radially aligned with said contact rows;
- (o) said spring means including another compression spring engaging the other of said wiping contact elements and located between the two compression springs first mentioned; 35
- (p) said stator providing an annular detent path between said insulating rows of said contact path;
- (q) said detent path having circumferentially spaced points of maximum radius axially aligned, respectively, with said stationary contacts of each of said contact rows; 40
- (r) said detent path having circumferentially spaced points of minimum radius axially aligned, respectively, with said insulating segments of each of said insulating rows;
- (s) a detent carried by and movable radially relative to said rotor and engaging said detent path; and 50
- (t) spring means biasing said detent radially outwardly into engagement with said detent path.
13. In a wiping contact rotary switch, the combination of:
- (a) an annular stator providing an annular, concave contact path;
- (b) said contact path including two axially spaced, parallel, annular contact rows of circumferentially spaced, stationary contacts; 60
- (c) said stationary contacts of one of said contact rows being axially aligned, respectively, with said stationary contacts of the other of said contact rows;
- (d) said contact path including two axially spaced, parallel, annular insulating rows of circumferentially spaced, insulating segments spaced axially from said contact rows, respectively; 65
- (e) said insulating segments of one of said insulating rows being axially aligned, respectively, with said insulating segments of the other of said insulating rows;
- (f) said insulating segments of each of said insulating rows being axially aligned, respectively, with the circumferential spaces between said stationary contacts of each of said contact rows; 70
- (g) said insulating rows being between said contact rows;
- (h) a rotor within said stator and rotatable about the axis thereof;
- (i) said rotor being provided therein with a longitudinally oriented, radially extending groove;
- (j) a wiping contact carried in said groove and movable radially therein relative to said rotor and slidably engaging said contact path;
- (k) the axial dimension of said wiping contact being sufficient to bridge said contact rows;
- (l) said rotor being provided therein with two axially spaced, radially extending holes coinciding with and larger than the width of said groove;
- (m) two compression coil springs respectively disposed in said holes and biasing said wiping contact radially outwardly into engagement with said contact path;
- (n) said stator providing an annular detent path between said insulating rows of said contact path;
- (o) said detent path having circumferentially spaced points of maximum radius axially aligned, respectively,

14

- the circumferential spaces between said stationary contacts of each of said contact rows;
- (g) said insulating rows being between said contact rows;
- (h) a rotor within said stator and rotatable about the axis thereof;
- (i) a wiping contact carried by and movable radially relative to said rotor and slidably engaging said contact path;
- (j) the axial dimension of said wiping contact being sufficient to bridge said contact rows;
- (k) spring means biasing said wiping contact radially outwardly into engagement with said contact path;
- (l) the diameter of said rotor approaching the inside diameter of said stator to provide a small, arc quenching annular clearance therebetween;
- (m) said stator providing an annular detent path between said insulating rows of said contact path;
- (n) said detent path having circumferentially spaced points of maximum radius axially aligned, respectively, with said stationary contacts of each of said contact rows;
- (o) said detent path having circumferentially spaced points of minimum radius axially aligned, respectively, with said insulating segments of each of said insulating rows;
- (p) a detent carried by and movable radially relative to said rotor and engaging said detent path; and
- (q) spring means biasing said detent radially outwardly into engagement with said detent path.
14. In a wiping contact rotary switch, the combination of:
- (a) an annular stator providing an annular, concave contact path;
- (b) said contact path including two axially spaced, parallel, annular contact rows of circumferentially spaced, stationary contacts;
- (c) said stationary contacts of one of said contact rows being axially aligned, respectively, with said stationary contacts of the other of said contact rows;
- (d) said contact path including two axially spaced, parallel, annular insulating rows of circumferentially spaced, insulating segments spaced axially from said contact rows, respectively;
- (e) said insulating segments of one of said insulating rows being axially aligned, respectively, with said insulating segments of the other of said insulating rows;
- (f) said insulating segments of each of said insulating rows being axially aligned, respectively, with the circumferential spaces between said stationary contacts of each of said contact rows;
- (g) said insulating rows being between said contact rows;
- (h) a rotor within said stator and rotatable about the axis thereof;
- (i) said rotor being provided therein with a longitudinally oriented, radially extending groove;
- (j) a wiping contact carried in said groove and movable radially therein relative to said rotor and slidably engaging said contact path;
- (k) the axial dimension of said wiping contact being sufficient to bridge said contact rows;
- (l) said rotor being provided therein with two axially spaced, radially extending holes coinciding with and larger than the width of said groove;
- (m) two compression coil springs respectively disposed in said holes and biasing said wiping contact radially outwardly into engagement with said contact path;
- (n) said stator providing an annular detent path between said insulating rows of said contact path;
- (o) said detent path having circumferentially spaced points of maximum radius axially aligned, respectively,

- tively, with said stationary contacts of each of said contact rows;
- (p) said detent path having circumferentially spaced points of minimum radius axially aligned, respectively, with said insulating segments of each of said insulating rows;
- (q) a detent carried by and movable radially relative to said rotor and engaging said detent path; and

5

- (r) spring means biasing said detent radially outwardly into engagement with said detent path.
